UNITED STATES PATENT OFFICE.

MILLARD KEITH SHARP, OF SHARPSBURG, ILLINOIS.

TEMPORARY STRINGER FOR TELEGRAPH, TELEPHONE, AND ELECTRICAL TRANSMISSION LINES.

Application filed January 9, 1926. Serial No. 80,320.

This invention has reference to a temporary stringer for telegraph, telephone and electrical transmission lines, and is adaptable for attachment to poles or other supports upon which wires are strung and includes wire engaging insulators and stretching means for placing a tension upon the wires during relief or repair work.

The invention comprehends a ratchet toothed bar adapted to be attached to a pole or support upon which wires are strung; a plurality of sleeves slidably arranged on said bar each provided with tooth engaging means and also with suitable insulator or non-conductor members adapted to be brought into coincidence and engage wires strung on said pole or support to take the place of the otherwise permanent insulators or non-conductors during repair or relief work, and includes a stretching means adapted to be actuated to place a uniform tension upon all of the wires engaged by the insulators or non-conductors on said sleeves.

That the invention may be more fully understood, reference is had to the accompanying drawings forming a part of the present description, illustrating a preferred embodiment of the invention, in which:

Figure 1 is a top plan view of my temporary stringer showing the same applied to a pole or other support having a permanent stringer or cross-head which is shown in dotted lines and showing how it functions as a temporary wire stringer;

Figure 2 is an elevation of Figure 1, and Figure 3 is a detail of a portion of the ratchet toothed bar and one of the sliding sleeves shown in partial section with the insulators or non-conductors and locking means thereon.

Like characters of reference denote corresponding parts throughout the figures.

In the drawings, A designates a pole or support of usual construction to which is shown attached a permanent stringer or cross-head B, braces C therefor and a plurality of insulators or non-conductors D, all of which are shown in dotted lines.

The temporary stringer which is to take the place of the permanent stringer or cross-head B and insulators or non-conductors D includes an elongated bar 1 preferably in length corresponding to a stringer B, provided with spaced sets of ratchet teeth 2 ar-

ranged preferably in the upper and lower edges of said bar. On this bar is slidably arranged a plurality of sleeves 3 having openings 4 disposed therein in their upper and lower body portions with struck up ears to and between which lever pawls 6 are pivoted, as best seen in Figure 3; the active ends of said lever pawls arranged to slide on the upper and lower toothed edges of said bar 1 and adapted to engage the same as shown. Springs 7 disposed between the sleeves and the hand engaging portions of said lever pawls hold their active ends in engagement with the bar 1 and in engagement with the ratchet teeth in manner shown. The sleeves may be moved along the bar by grasping the lever pawls and drawing or pushing the sleeves along the bar and by tightly gripping the lever pawls and compressing the springs 7, the pawls may be released in the bar, as will be understood. To one end and to the upper and lower sides of the sleeves 3 are connected insulators or non-conductors 8, which may be of any approved construction.

The bar 1 is preferably provided mediate its ends with an offset body portion 9, see Figure 1, to permit a partial embracing of the pole or support A and to allow for placing of the bar 1 so that its opposite end portions may lie parallel and in front of the insulators or non-conductors D on the stringer or cross-head B, in the manner shown in Figures 1 and 2.

The bar 1 includes in its structure a jack comprising a threaded member 10 with a sleeve-like portion 11 telescoped thereon and having a grip 12 adapted to engage the pole or support A. The member 10 and the sleeve portion 11 are connected at one end to the bar 1 and the main body portions thereof are spaced from and lie parallel to the bar 1 as shown in Figure 1. Connected with the inner end of the sleeve-like portion 11 are meshing bevel gears 13 and 14, the latter having a threaded engagement with the threads of the member 10. To actuate the gearing, to move the bar 1 and member 10, in relation to the sleeve-like portion 11, there is provided a hand lever 15 fulcrumed to the axis of the bevel gear 13 and provided with the toothed segment 16 adapted to engage the teeth of the bevel gear 13 to rotate it in opposite directions. To fold the jack,

the threaded member 10 is jointed, as at 17. I have also jointed the bar 1, as at 18 to permit it to be collapsed.

To the opposite ends of the bar 1 are connected bracing members 19 which, when the bar 1 is in operative position, may be attached in any suitable manner to the pole or support A for staying the said stringer bar in operative position.

10 In the use of the invention, assuming for the purpose of explanation, that a stringer or cross-head B is damaged, cracked or broken or is out of repair to such an extent that restringing of wires is necessary, the
 15 temporary stringer is mounted in position and the sleeves 3 moved thereon into position to bring the insulators or non-conductors B into engagement with the wires. The sleeves are then moved to locked position
 20 to place a preliminary tension upon the wires at which time or before, if desired, the braces 18 may be secured in position. This done, the final tension may be placed upon the wires by actuating the lever 15. The
 25 wires are now held by this temporary stringer and work may be proceeded with to correct the damage of the stringer or cross-head B to whatever extent may be necessary even to the extent of replacing the stringer
 30 or cross-head B. It is obvious therefore, that by the use of this invention, that a linesman may effectively and efficiently repair stringers or cross-heads B in an efficient and quick manner and without danger
 35 to himself in the event the wires are electrical transmission wires and without entanglement or contact of any wires.

What I claim is:—

1. A temporary stringer for telegraph, telephone and electrical transmission lines, comprising an elongated bar provided with spaced sets of ratchet teeth along opposite edges, means for attaching the stringer to a support including stretching means, and a plurality of sleeves slidably arranged on said bar and provided with insulators and ratchet toothed engaging means. 40

2. A temporary stringer for telegraph, telephone and electrical transmission lines, comprising an elongated bar bowed mediate 50 its ends to partially embrace a support, said bar being provided with a plurality of spaced sets of ratchet teeth on opposite edges thereof, a plurality of sleeves slidable on said bar and having insulators attached thereto, lever pawls mounted on said sleeves to yieldingly engage the said bar and the ratchet teeth thereon and means to attach the bar to a support, including a stretching means comprising telescopic members and 55 associated gearing.

3. In a device of the character described, a bar provided with spaced sets of ratchet teeth along opposite edges, a plurality of sleeves slidable on said bar, each sleeve having oppositely disposed insulator members, spring held lever pawls pivoted on said sleeves and arranged to have engagement with the teeth on said bar, a support engaging means comprising a stretcher composed of telescopic members, one of which is threaded, and gearing in operative engagement with said threaded member. 65

In witness whereof, I have hereunto affixed my hand this 28th day of Dec., 1925.

MILLARD KEITH SHARP.
